UNITED STATES PATENT OFFICE.

GEORGE J. PFEIFFER, OF PROVIDENCE, RHODE ISLAND, ASSIGNOR TO CROMPTON & KNOWLES LOOM WORKS, OF WORCESTER, MASSACHUSETTS, A CORPORATION OF MASSACHUSETTS.

DOBBY.

1,174,895.

Specification of Letters Patent. Patented Mar. 7, 1916.

Application filed March 25, 1914. Serial No. 827,173.

To all whom it may concern:

Be it known that I, GEORGE J. PFEIFFER, a citizen of the United States, residing at Providence, in the county of Providence and 5 State of Rhode Island, have invented a new and useful Dobby, of which the following is a specification.

This invention relates to a doby and particularly to a doby in which a plurality of indicating fingers control the operations of 10 the harnesses. These fingers are usually formed from cast metal and are frequently broken while in use. The replacement of a broken finger under the usual conditions requires a considerable expenditure of both 15 time and labor, as substantially the entire set of fingers must often be released from operative position before a broken finger can be removed and replaced.

Accordingly, one feature of my invention 20 consists in the provision of improved devices for supporting the indicating fingers, so constructed that any finger can be removed and replaced without displacing any 25 other finger or the support therefor. A somewhat similar inconvenience arises in the 30 operation of the ordinary doby whenever it is necessary to replace the guiding rack which positions and separates the operating ends of the indicating fingers. The replacement of this rack ordinarily involves the release of all of the indicating fingers of both 35 sets from operative position and their subsequent repositioning.

A further feature of my invention consists therefore in the provision of an improved construction of guiding rack involving the use of a separate guiding member for 40 each set of fingers, each member being removable and replaceable independently of the other member.

My invention further consists in certain devices, arrangements and combinations of parts which will be hereafter described and 45 more particularly pointed out in the appended claim.

A preferred form of my invention is shown in the drawings in which—

Figure 1 is a side elevation of a portion of 50 a doby showing my improved device applied thereto; and Fig. 2 is a partial end elevation of the parts shown in Fig. 1.

The numeral 10 indicates a portion of the supporting frame of a doby upon which a 55 plurality of indicating fingers 11 and 12 are

pivotal mounted. In order that any one of these fingers may be readily removed and replaced without disturbing the remaining fingers I provide a substantially semicircular recess 13 in the lower edge of each finger, so 60 positioned as to coöperate with the transversely extending cylindrical bar 14 secured in the frame 10. A transverse rod 15 is also 65 detachably secured in the frame 10 and serves to prevent accidental upward displacement of the indicating fingers. With this construction it will be evident that, when the rod 15 is in operative position, the fingers are securely held in the doby and are at the same time free to move about the 70 bar 14 as a center. When the bar 15 is removed, the fingers 11 and 12 will remain in their normal operative positions and any one of them may at the same time be readily removed by simply lifting it off of the bar 75 14. The replacement of any one of the fingers 11 and 12 thus becomes an exceedingly simple operation and the expenditure of time and labor involved therein is reduced to a 80 minimum.

The fingers 11, which may be designated as straight indicating fingers, coöperate with lifting rods 16 which control the upper hooks of the doby, (not shown). The fingers 12 have their operating ends upturned 85 and serve to control the lower hooks of the doby (not shown). In order that each finger may be held in transverse alinement with its respective lifting rod or hook it is necessary that a guiding rack be provided for 90 positioning the fingers. These racks are commonly formed of cast metal and are subject to occasional accidental breakage. It has been customary to form the entire guiding structure for the full set of fingers as a 95 single member and with this construction it will be evident that in case of breakage it is necessary to remove the entire rack and to release all of the indicating fingers from their operative position. It is then a matter 100 of considerable labor, after the new rack is in place, to correctly insert and position the large number of fingers ordinarily used.

To avoid the disadvantages above referred to I have formed the guiding rack in my 105 improved doby in two parts 17 and 18. The lower member is detachably secured to the under side of a portion of the supporting frame 10 by screws 19 and contains a plurality of separate open compartments 20 110

which are adapted to receive and position the operating ends of the fingers 11. These compartments are formed by bars 21 which are secured at their upper and lower ends to transverse bars 22 and 23. The upper bar 23 serves to retain the fingers in position when the lifting rod 16 is removed and it also serves as one of the guides for the lifting rods 16. The rods 16 also extend between the bars 21 which act as guides upon two sides and a rod 24 constitutes a guide for the lifter rods upon the fourth side and opposite the bar 23. The upper member 18 of the guiding rack is detachably secured to the upper portion of the frame 10 by screws 25 and comprises a transversely extending bar 26 having a plurality of members 27 depending therefrom and serving to transversely position the up-turned ends of the fingers 12. In order to preserve the alternate arrangement of the fingers 11 and 12 the depending members 27 are arranged substantially vertical over the compartments 20 of the lower guiding member 17. With this construction it will be evident that either guiding member 17 or 18 may be removed and replaced without disturbing the adjustment of the other guiding member or of the indicating fingers positioned thereby.

Having thus described my invention it will be evident that changes and modifica-

tions can be made therein by those skilled in the art without departing from the spirit and scope thereof and I do not wish to be limited to the details herein disclosed but

35

What I do claim is:—

A dobby having, in combination, a plurality of lifter rods, a supporting frame, a plurality of hook-controlling fingers, each alternate finger having a straight bearing portion engaging the lower end of a lifter rod for controlling one of the upper hooks, and the remaining fingers being upturned at one end to directly engage the lower hooks, each of said fingers having a semi-circular recess in its lower side, a rod mounted in said frame and extending transversely beneath said fingers in the recesses thereof, and a second rod detachably mounted in said frame, overlying said fingers, and preventing displacement or removal thereof so long as said rod is in position but permitting separate removal of each finger after the rod is withdrawn from operative position.
